UNITED STATES PATENT OFFICE

GEORGE D. WILKINSON, OF OAK PARK, AND ELMER D. PELLEGRIN, OF DES PLAINES, ILLINOIS, ASSIGNORS TO CRIBBEN & SEXTON COMPANY, OF CHICAGO, ILLINOIS, A CORPORATION OF ILLINOIS

DESIGN FOR A RANGE

Application filed May 7, 1931. Serial No. 39,756. Term of patent 7 years.

To all whom it may concern:

Be it known that we, GEORGE D. WILKINSON, a citizen of the United States, residing at Oak Park, in the county of Cook, State of Illinois, and ELMER D. PELLEGRIN, a citizen of the United States, residing at 724 Arlington Avenue, Des Plaines, in the county of Cook, State of Illinois, have invented a new, original, and ornamental Design for a Range, of which the following is a specification, reference being

had to the accompanying drawing, forming a part thereof, in which the drawing is a perspective view of a range showing our new design.

We claim:

The ornamental design for a range as shown.

GEORGE D. WILKINSON.
ELMER D. PELLEGRIN.
